UNITED STATES PATENT OFFICE.

CHARLES STOLLBERG, OF TOLEDO, OHIO, ASSIGNOR TO AMERICAN CAN COMPANY, OF NEW YORK, N. Y., A CORPORATION OF NEW JERSEY.

CONTAINER.

1,317,738.

Specification of Letters Patent.

Patented Oct. 7, 1919.

Application filed August 22, 1914. Serial No. 858,145.

To all whom it may concern:

Be it known that I, CHARLES STOLLBERG, a citizen of the United States, residing in Toledo, in the county of Lucas and State of 5 Ohio, have invented a new and useful Improvement in Containers, of which the following is a specification.

My invention relates to sheet metal containers and has more particular reference to 10 sheet metal containers adapted for the packaging and marketing of biscuits, crackers and the like wherein a sheet metal body composed of flat interengaging walls and having an open side adapted to be closed by a cover 15 is provided for packing the contents for shipment and from which the contents are to be sold as required.

Sheet metal cracker and biscuit boxes are, according to usual custom, seldom sold by 20 the baker to the retail trade, the return of the box or container being usually required and secured by a deposit of fifty cents per box or container. These boxes are recovered by the baker and refilled as many times as 25 their condition will permit. It is extremely desirable, therefore, that they be constructed of the greatest possible strength and in such manner that they are not easily so badly dented that they cannot be repaired to main- 30 tain a new and fresh appearance.

The principal object of this invention is to provide a cracker box or the like of maximum strength consistent with economy of production. A part of the box frequently 35 bent beyond repair in the past has been the end of the body provided with a cover or closure.

It is an object of this invention to so construct the box that the open end will be 40 strongly reinforced and will, throughout repeated use, present a smooth, even and true appearance.

A further object of the invention is to reinforce the upper edge of such a box to pro- 45 vide a flat and substantially true surface to engage the closure, said reinforce being so constructed and arranged that it will always be tight when in place and thereby prevent looseness and rattling of the parts.

Other objects and advantages of the invention will be apparent as it is better under- 50 stood from the following description when considered in connection with the accom- 55 panying drawing illustrating a preferred embodiment thereof.

Referring to the drawing,

Figure 1 is a top plan view with parts broken away of a container or cracker box embodying my invention; and

Fig. 2 is a partial sectional view taken 60 substantially on the line 2—2 of Fig. 1 with the cover of the box in closed position.

For the purpose of illustrating my invention I have shown it embodied in a cracker box of a well known general design comprising a rectangular body 3 and a cover 4 hinged at 5 in any preferred or suitable manner to the body.

The upper edges of the walls of the body are provided with a continuous reinforce 6 70 composed of a plurality of sections 7. Each of these sections consists of a flat angle strip of metal adapted to be placed at a corner 8 at the open side and the lengths of the legs 9 of the sections are of appropriate dimension to permit them to interlock at their ends with adjacent sections. The sections 7 are interlocked by dove-tail connections, an enlarged tongue 10 being provided on one leg of each section and a suitably formed recess 11 being provided on the other, said tongues and recesses being adapted to interlock the sections as seen in Fig. 1. The sections thus form a continuous flat band adapted to extend inwardly from the upper edge of the 80 side walls of the container where it is held in place by bending the edges of the side walls inwardly at 12, downwardly at 13 and back beneath the band at 14 so that the upper edge of each side wall embraces the 90 band. These edges are cut away at 15 to provide a smooth fit and to dispose the inwardly extending portions 16 of the edges of all four side walls in substantially a single plane against which the under surface of the 95 cover may rest when the container is closed.

In accordance with the usual custom the cover is provided with a downwardly extending flange 17 adapted to fit snugly against the outer surface of the side walls so that 100 two pairs of contacting surfaces are provided at the juncture of each side wall and the cover. This forms a good, substantial seal when the cover is merely lowered to closed position, which in large measure will 105 prevent the entrance of moisture into the container and thereby maintain the crackers, biscuits or other contents in crisp, fresh condition. The sections 7 of the band act as corner braces and being interlocked together 110

are held in tight relationship when the edges of the side walls are bent around them to secure the band in place. The band forms substantially a continuous inwardly extending flange at the top of the body of the box which presents a smooth, even, metal surface not readily bent at any point. This arrangement, therefore, not only materially strengthens the structure of a box but plays an important part in maintaining a fresh, new appearance after the box has been re-filled repeatedly, as the upper surface of this flange may be readily buffed to maintain it in a shining condition.

15 It is thought that the invention and many of its attendant advantages will be understood from the foregoing without further description, and it will be apparent that various changes may be made in the form, construction and arrangement of the parts without departing from the spirit and scope of the invention or sacrificing any of its material advantages, the form hereinbefore described being merely a preferred embodiment thereof.

20

25

I claim:

1. A container comprising a sheet metal angular body, and a reinforcement about

the mouth of the body consisting of four separate flat and uniform metal sections, 30 each section being continuous around the corner of the container, said sections abutting against each other at the four sides of the container, and said sections being tightly inclosed in a flat fold of the edge of the body 35 which is bent inward over the tops of said sections and thence down at their inner edges and thence outward beneath said sections.

2. A container comprising a sheet metal angular body, and a reinforcement about the 40 mouth of the body consisting of four separate flat and uniform metal sections, each section being continuous around the corner of the container, said sections abutting against each other at the four sides of the 45 container and having interlocking tongues and recesses, and said sections being tightly inclosed in a flat fold of the edge of the body which is bent inward over the tops of said sections and thence down at their inner 50 edges and thence outward beneath said sections.

CHARLES STOLLBERG.
